The ornamental design for a tattooing apparatus, as shown and described.

DESCRIPTION

FIG. 1 is a front perspective view of a tattooing apparatus; FIG. 2 is an enlarged front view of the tattooing apparatus of FIG. 1;

FIG. 3 is an enlarged rear view of the tattooing apparatus of FIG. 1;

FIG. 4 is a first side view of the tattooing apparatus of FIG. 1;

FIG. 5 is a second side view of the tattooing apparatus of FIG. 1;

FIG. 6 is a top view of the tattooing apparatus of FIG. 1; FIG. 7 is a bottom view of the tattooing apparatus of FIG. 1;

FIG. 8 is a front perspective view of the tattooing apparatus of FIG. 1, where a needle cartridge is in an extended state; and,

FIG. 9 is a front perspective view of the tattooing apparatus of FIG. 8, where the tattooing apparatus is disposed in a holder.

The broken lines, including both the dashed-dot-dot-dashed and dashed lines, depict unclaimed portions of the tattooing apparatus and form no part of the claimed design. For example, the needle cartridge of FIG. 8 and the holder of FIG. 9 are shown with broken lines and form no part of the claimed design.
